UNITED STATES PATENT OFFICE.

JAMES L. LEE, OF CHICAGO, ILLINOIS.

DESIGN FOR A CAM FOR PRINTING-PRESS FRAMES.

SPECIFICATION forming part of Design No. 27,550, dated August 17, 1897.

Application filed August 31, 1894. Serial No. 521,874. Term of patent 7 years.

To all whom it may concern:

Be it known that I, JAMES L. LEE, a citizen of the United States, residing at Chicago, in the county of Cook and State of Illinois, have 5 invented and produced a certain new and original Design or Useful Shape for Cams for Printing-Press Frames, of which the following is a full, clear, and exact specification, reference being had to the accompanying drawings, in which--

Figure 1 is a side elevation of a cam embodying my design, and Fig. 2 is an edge view thereof.

The leading features of my design consist 15 of the cam portion A, constituting a finger-like projection having its edge formed on a compound curve, and the bracket portion B, from which the finger or cam portion projects. The bracket portion B is provided with a num-

ber of perforations b, and curving outwardly 20 and upwardly from the end of the bracket portion is the finger-like portion A, both sides of which gradually converge on compound curves to an attenuated end or point. Extending downwardly from the finger-like portion A and merging into the bracket portion B is a web C.

Having thus described my invention, what I claim as new, and desire to secure by Letters Patent, is—

The new and original design or useful shape 30 for a cam for printing-press frames, substantially as herein shown and described.

JAMES L. LEE.
